UNITED STATES PATENT OFFICE.

GOVE S. BOYLAN, OF WASHINGTON, DISTRICT OF COLUMBIA.

TAKE-UP MECHANISM FOR KINETOSCOPES.

1,377,112.

Specification of Letters Patent.

Patented May 3, 1921.

Application filed October 10, 1919. Serial No. 329,818.

To all whom it may concern:

Be it known that I, GOVE S. BOYLAN, a citizen of the United States, residing at Washington, in the District of Columbia, have invented new and useful Improvements 5 in Take-Up Mechanism for Kinetoscopes, of which the following is a specification.

The object of my present sole invention is the provision of a take-up mechanism for 10 kinetoscopes in which are comprised means to overcome the inertia of a film reel at the commencement of a winding operation, and means to assure the imposition of even tension 15 at all times on the film, as well as the proper minimum tension to bring about the desirable snug winding of the film on the reel, so that initially the reel is driven through one connection, and then after some 20 of the film is taken up on the reel, the reel is driven through another connection, or through the last-named connection in association with the first-named connection.

To the attainment of the foregoing, the invention consists in the improvement as 25 hereinafter described and definitely claimed.

In the accompanying drawing, hereby made a part hereof:

The figure is a diametrical section illustrative of the best practical embodiment of 30 my invention that I have as yet devised.

Referring by numeral to the said drawing:

5 is a film reel carried by the shaft 6. The reel may be removably secured on the shaft 35 by any approved means without affecting my invention; the shaft 6 being shown as provided with a key 6^a, to assure turning of the reel by the shaft. Fixed by a thread or other suitable means on the shaft 6 at the 40 outer side of the flange 9 thereof, is a cylindrical body 8 of wood or other material appropriate to its purpose. At its outer end, the shaft 6 is threaded, as indicated by 45 6^b for the engagement of a nut 6^c and a jam nut 6^d, and at the inner side of the nut 6^c, and surrounding the shaft 6, are a washer 10 and a coiled spring 11.

At 12 is the shell of a support, of circular form in cross-section, that is flanged at 50 13 for attachment to a kinetoscope frame.

Loosely surrounding the shaft 6 and opposed to the outer end of the shell 12, is a pulley 14 on which is a lateral tubular portion 15 that snugly receives the cylindrical 55 body or element 8.

Contained in the annular space between

the bore wall of the shell 12 and the outer surface of the tubular member 15 is an anti-friction bearing 20 which may be of the construction shown, or of any other construction appropriate to my invention. 60

Keyed at 21 on the shaft 6 or otherwise engaged with said shaft so as to turn therewith and move laterally thereon, is a friction disk 22, subject to the pressure of the 65 spring 11 and opposed to one side of the pulley 14. In order to contribute to the efficiency of this part of my improvement, I prefer to interpose a slip-disk 23, of paper or other suitable material, between the disk 70 22 and the pulley 14.

The pulley 14 is designed to be driven through a belt, not shown, from a motor, also not shown, in the ordinary well known manner. I do not desire, however, to be 75 understood as confining myself to the said specific driving connection, inasmuch as any other driving connection may be employed without affecting my invention, therefore it is to be understood that the term "pulley," 80 as herein employed, is intended to comprehend any kind of wheel or gear adapted to be rotated.

With my invention, the power required to rotate the reel when full is not applied to the 85 reel at the commencement of a winding operation when the reel is light in weight. On the other hand, by reason of my improvement, the excess power at the commencement of a winding operation is not transmitted to 90 the reel. This will be better understood when it is stated that at the commencement of a winding operation the reel is turned through the medium of a driving connection including the pulley 14, the disk 22 and 95 the shaft 6, and because of the slippage between the pulley 14 and the disk 22, there will be no tendency of the reel to take up or wind the film faster than the ordinary mechanism releases the film, and as a result 100 there will be no strain on the film held in check by the usual sprocket engaging its apertures, and no liability of the walls of the apertures being subjected to undue wear. Then when the weight of the wheel 5 is increased by the addition of the taken-up 105 film thereon, the friction between the driven element 8 and the driving element 15 will be increased, with the result that the proper amount of power to rotate the reel as the same increases in weight, will be automatically supplied in corresponding ratio, to the 110

increase of weight. It will also be apparent that the capacity of the elements 8 and 15 to slip with respect to each other, contributes to the imposition of even tension 5 and the even speed of the film throughout a run thereof, and in this way injury to the walls of the apertures in the film will also be precluded, and the usefulness of the film will be materially prolonged. Manifestly 10 the driven element 8 is movable vertically by gravitation or downward movement of the reel, or in other words, the two are movable vertically as a unit.

The foregoing will perhaps be better understood 15 when it is stated that owing to the different speeds of the body 8 which are encountered, namely, the maximum at the start and minimum at the close of the winding operation, and the amount of pressure exercised 20 between the driving and driven surfaces at these opposite stages, it is necessary to make the diameter of body 8 so small in order that it shall not require and dissipate an unnecessary amount of power 25 during the latter part of the operation that considerable trouble is encountered in getting the body into motion as the machine is started. There is a fire risk which should not be overlooked in connection with the 30 above mentioned difficulty. It is essential that the moment the mechanism begins to pay out film the reel and take-up apparatus should function immediately and satisfactorily. The highest speed is required at this 35 stage and due to the inertia of the reel this speed is not obtained until sufficient film has been paid out to allow the reel now under way to develop a speed above normal which must be checked by the film itself, thereby 40 causing a jerk upon it, which not only produces a visible damage to the walls of the apertures but is liable to break it.

It will be gathered from the foregoing 45 that by virtue of my improvement and incidental to a winding operation, the reel 5 is first rotated through the pulley 14, disk 22 and shaft 6, and afterward the reel is rotated through the medium of the pulley 14, the driving element 15, the driven element 50 8 and the shaft 6. It will also be appreciated that frequently when once the reel is under motion, the power applied to the shaft 6 is in part through the friction between the disk 22 and the pulley 14, and in 55 part through the friction between the member 15 and the driven element 8. The tension of the spring 11 is preferably adjusted to a point where the power transmitted to shaft 6 is just sufficient to bring about the 60 rotation of the reel 5 when the same is empty and therefore light in weight. A preferable mode of operation is to adjust the tension on starting, so that the reel will be put in motion as quickly as is desired, 65 and no more. When the reel takes up film

and becomes hard to turn because of its increased weight, the said weight serves to increase the friction between the driven element 8 and the driving element 15 to a point where the power transmitted to the shaft is 70 ample to compensate for the increasing weight of and diminishing of tension in the film. At the point where the disk 22 is unable to provide for the rotation of the reel, the driving element 15 and the driven element 75 8 automatically take over the duty of supplying the power required to wind the film. The power referred to varies as the weight increases on the reel 5 in such proportion as to maintain an even tension on the 80 film throughout the varying of the reel. It will be apparent that any size reel may be handled in the manner referred to by varying the sizes of the parts.

Having described my invention, what I 85 claim and desire to secure by Letters-Patent, is:

1. In a take-up mechanism for kinetoscopes, the combination of a support, a reel, a driven friction element connected with 90 the reel to transmit rotary motion thereto, a driving friction element surrounding the driven element and frictionally engaging the same and mounted in the support, whereby tendency of the reel to move downwardly 95 increases the friction between the driving and driven element, and a supplemental driven friction element connected with the reel and arranged for coöperation with the first-named driven friction element. 100

2. In a take-up mechanism for kinetoscopes, the combination of a reel, means through which the reel is initially rotated when the reel is empty and light, and other means through which in association with 105 the first-named means the reel is rotated after the weight of the reel is increased by the taking up of film thereon.

3. In a take-up mechanism for kinetoscopes, the combination of a reel, means 110 through which the reel is initially rotated when the reel is empty and light, and other means through which in association with the first-named means the reel is rotated after the weight of the reel is increased by 115 the taking up of film thereon; the said means being adapted to automatically accommodate the same to the increase of weight of the reel.

4. In a take-up mechanism for kinetoscopes, the combination of a reel, friction means through which the reel is initially rotated when the reel is empty and light, and friction means associated with the first-named means for rotating the reel after the 125 weight of the reel is increased by the taking up of film thereon.

5. In a take-up mechanism for kinetoscopes, the combination of a support, a shaft 130 to carry a reel, a tubular driving element

- surrounding the shaft, a cylindrical body carried by the shaft and constituting a driven element snugly fitting in the tubular element, an anti-friction bearing intermediate.
- 5   ate the support and the tubular driving element, means through which the tubular driving element is rotated, and a friction disk keyed on the shaft and frictionally held under yielding pressure against said means.
- 10   6. In a take-up mechanism for kinetoscopes, the combination of a support, a shaft to carry a reel, a tubular driving element surrounding the shaft, a cylindrical body carried by the shaft and constituting a
- 15   driven element snugly fitting in the tubular element, an anti-friction bearing intermediate.

ate the support and the tubular driving element, means through which the tubular driving element is rotated, a friction disk keyed on the shaft and yieldingly pressed toward said means, and a disk loosely interposed between said means and the disk keyed to the shaft. 20

7. In a take-up mechanism for moving picture machines, a take-up shaft, and means thereon, whereby initial power and following power are applied to the shaft; the initial power to start the shaft, and the following power to rotate the shaft in the ratio that film is taken up on the same. 25   30

In testimony whereof I affix my signature.
GOVE S. BOYLAN.
